SAFETY RAZOR

Joseph L. Bronstein, Milwaukee, Wis., now by
change of name Joseph L. Brans

Application July 7, 1937, Serial No. 152,340

9 Claims. (Cl. 30—43)

This invention relates in general to safety razors, and more particularly to razors of the type having a stationary cutter in shearing engagement with a rotary cutter.

5 Safety razors are known in which a movable cutter is given a reciprocatory motion in contact with a stationary cutter by means of an electric motor of the vibrating type. Such motors however may not conveniently be adapted to give a 10 large number of cutting strokes per second, and it is therefore preferable to utilize a rotary cutter driven by a conventional electric motor or by other suitable means adapted to rotate the cutter at any speed which may be required for obtaining the desired number of cuts per second.

To insure the necessary contact between the cutting edges of the stationary and rotary cutters, it is preferable to utilize a rigid stationary cutter containing a rotary cutter resiliently urged thereagainst by a suitable force such as centrifugal force. The stationary cutter is preferably provided with cutting apertures in the form of slots of such shape as to guide the hair therein, the skin being drawn into such slots by the suction 25 of a fan to obtain the closest possible shave.

It is, therefore, an object of the present invention to provide a safety razor of the rotary shearing type in which a rotary cutter is resiliently urged against a rigid stationary cutter.

30 Another object of the present invention is to provide a safety razor having apertures so formed as to guide the hair therein.

Another object of the present invention is to provide a safety razor in which a suction is exerted at the cutting edges of the stationary cutter to draw the skin into close proximity with the rotary cutter.

Objects and advantages other than those above set forth will be apparent from the following description when read in connection with the accompanying drawing, in which:

Figure 1 is a view partially in elevation and partially in longitudinal cross-section of one embodiment of the present invention in which the cutters are urged into mutual engagement by the thrust exerted by the electric motor driving the rotary cutter;

Fig. 2 is an enlarged view in cross-section taken on plane II—II in Fig. 1;

Fig. 3 is a view partially in elevation and partially in longitudinal cross-section of a modified embodiment of the present invention in which the cutters are urged into mutual engagement by a spring;

Fig. 4 is an enlarged view in cross-section taken on plane IV—IV in Fig. 3;

Fig. 5 is a view partially in elevation and partially in longitudinal cross-section of another modified embodiment of the present invention in which the cutters are urged into mutual engagement by the joint action of a spring and of centrifugal force;

Fig. 6 is an enlarged view in cross-section taken on plane VI—VI in Fig. 5;

Fig. 7 is an enlarged fragmentary view of the cutters illustrated in Figs. 1 and 2, and

Fig. 8 is an enlarged view in elevation of the rotary cutter illustrated in Figs. 5 and 6.

Referring more particularly to the drawing by characters of reference, reference numeral 10 in Fig. 1 designates the body or casing of a razor which is to be held in the hand when the razor is being used. Such casing is of generally hollow cylindrical form, and may be made of any suitable material such as pressed sheet metal or molded plastic material. If the latter material is utilized, the casing is preferably made in two complementary halves which are held in proper relative position by means of a cover 11 and of a 25 stationary cutter 12. Cover 11 and cutter 12 may be fastened on casing 10 in any suitable known manner such as by screwing.

Cutter 12 is of hollow frusto conical shape, and is made of steel of razor blade grade having a 30 thickness as reduced as is found practicable. Cutter 12 contains a rotary cutter 13 which is likewise hollow, of frusto conical shape, and which is mounted on a hub 14. Hub 14 is fastened in any suitable known manner on a spindle 35 15 arranged for rotary movement within casing 10 coaxially therewith. Spindle 15 may be driven by any suitable motor such as an electric motor 16 mounted within casing 10.

Motor 16 may be of any known type and is 40 represented as being of the induction type having a stator 17 provided with an exciting winding 18 to be connected to any suitable source of alternating current. The rotor 19 of the motor is preferably of the squirrel cage type. If cutter 45 13 is to be rotated at the same speed as rotor 19 the rotor is directly connected with the cutter through spindle 15, but it will be understood that gears or other speed changing means may be interposed between rotor 19 and cutter 13 to obtain rotation of the cutter at the desired speed. Rotor 19 is axially displaced with respect to stator 17 to produce a thrust on spindle 15 urging cutter 13 into shearing engagement with cutter 12 by the axial component of the magnetic attraction 55

of stator 17 on rotor 19. Such magnetic thrust may take effect by so shaping spindle 15 that the spindle may take a certain amount of axial play in the bearings 21 of motor 16.

5 Spindle 15 carries a fan impeller which is preferably of the centrifugal type comprising a plurality of suitably shaped vanes mounted on a hub carrying a disc for guiding the flow of air through the impeller. The fan structure is completed by a perforated diaphragm 23 held in a groove of casing 10, the aperture through the diaphragm forming a suction passage connected with the space within cutters 12 and 13.

10 Fan 22 is provided with a discharge passage 15 24 which may conveniently be formed by a lateral tubule on casing 10. Passage 24 is closed by a bag permeable to air and preferably made of loosely woven fabric for collecting hair sheared by the cutters and drawn into the fan by the 20 suction thereof. The bag, designated by 25, is attached to passage 24 by any suitable known means such as a metal bushing 26 connected to passage 24 by a bayonet fastening. Return of the hair from the bag into the fan by gravity 25 when the fan is inoperative is prevented by a suitable check valve 27. In its simplest form, such valve may consist of a flap of rubber or other yieldable material attached loosely on the end of bushing 26 remote from fan 22 for opening passage 24 only when the fan is operating.

20 It will be observed that cutter 12 is provided with a plurality of circular rows of slots lying on generatrix lines of the conical surface thereof. Each slot has an elongated rectangular portion 35 extending through the thickness of the cutter wall to form an aperture therein, and is terminated at least at one end thereof by a flaring portion of variable depth less than the thickness of the cutter wall. The slots of any row are arranged in alignment with the portions of the cutter wall separating the slots of the other row or rows, so that any generatrix line of the conical surface portion of the cutter provided with slots meets at least one of the slots.

30 Cutter 13 is likewise provided with slots to form cutting edges lying on generatrix lines of cutter 13 in circular rows opposite the rows of slots of cutter 12. The slots of cutter 13 are preferably of rectangular shape having the long edges thereof substantially on generatrix lines of the cutter for cooperating with the edges of the rectangular portions of the slots of cutter 12. The result of such slot arrangement is that the cutting edge of any slot of cutter 13 simultaneously engages 55 all points of the cutting edge of any slot of the corresponding row of cutter 12.

45 The rows of slots of cutter 13 extend over the entire circumference thereof, and the rows of slots of cutter 12 may be arranged likewise. It is 60 however preferable to provide slots in only a circumferentially circumscribed area of cutter 12 as shown on the drawing. The amount of heat produced by friction between the cutters may then be reduced by providing cutter 12 with a circumferentially stepped inner surface which is accordingly in contact with cutter 13 only over circumferentially circumscribed areas. Such areas comprise necessarily the area of cutter 12 provided with slots as is apparent in Fig. 2, in which 65 the thicknesses of the cutters are exaggerated to render the drawing clearer, and may also comprise a diametrically opposed area for aiding in guiding the rotary cutter.

70 When the razor is to be used, motor 16 is energized to drive cutter 13 and fan 22. Casing 10 is

held in the hand and the slotted portion of cutter 12 is applied against the skin to be shaved. Such slotted portion is then drawn over the surface of the skin in the direction of the slots. During such movement the hair is guided into the slots by the flared portions thereof, and as a result of the staggering of the slots of the different rows every point of the area to be shaved over which the razor is drawn is thus faced at some time by at least one of the slots. Each hair 10 thus penetrates into one of the slots where it is sheared in a positive manner by the engagement of parallel cutting edges of the two cutters.

15 At the same time fan 22 creates a suction in the space within the cutters whereby air is drawn through the slots of the cutters and is expelled through passage 24 and bag 25. The sheared hair is carried by such flow of air into bag 25, wherein the hair is retained. The suction of fan 22 evacuates the space within cutter 13, and the 20 skin is caused thereby to be drawn into the slots of cutter 12 in close proximity with the cutting edges of cutter 13, thus insuring as close a shave as is obtainable even with razors of the conventional unguarded blade type.

25 In the embodiment illustrated in Figs. 3 and 4 the casing of the razor consists of two half shells 28 of molding material comprising a cylindrical portion enclosing motor 16 and a generally frusto conical portion. The two halves of casing 28 may 30 be maintained assembled by cover 11 and by a ring 29 screwed thereon. The stationary cutter consists of the frusto conical portion of one of the halves of casing 28 having embedded therein a curved plate 30 of steel of razor blade grade 35 provided with the rows of slots above defined with respect to the embodiment illustrated in Figs. 1 and 2. The inner surface of the slotted area of plate 30 is ground to fit the complementary surface of the associated rotary cutter. The rotary 40 cutter may be similar to cutter 13 illustrated in Figs. 1 and 2 or may be a cutter 13' provided with only one row of slots in which the slots are of sufficient length to engage both rows of slots of cutter 30.

45 In the present embodiment rotor 19 of motor 16 is assumed to be axially centered with respect to the associated stator 17, which therefore does not exert any axial thrust thereon. Cutter 13' may then be urged against plate 30 in shearing 50 engagement therewith by means of a spring 31 mounted on cover 11 and acting on the end of spindle 15. Since the area of contact between cutter 13' and plate 30 is not symmetrical with respect to the axis of the cutter the thrust exerted by spring 31 causes spindle 15 to be also subjected to a radial thrust which is transmitted thereby to the bearings of motor 16. The operation of the present embodiment is identical to that of the previously described embodiment.

60 The embodiment illustrated in Figs. 5 and 6 utilizes previously described casing 10, stationary cutter 12 and motor 16, but in the present embodiment the motor is mounted eccentrically within the casing, and the rotary cutter 32 65 mounted on hub 14 is likewise arranged within cutter 12 eccentrically with respect thereto. Cutter 32 comprises a disc portion mounted on hub 14 and bearing a small number of resilient cutting blades having cutting edges arranged on 70 generatrix lines of a conical surface closely adjacent the inner conical surface of cutter 12. Cutter 32 is urged into engagement with cutter 12 by means of a spring 31.

75 When the cutter is rotated by motor 16 the 75

cutter blades are urged radially outward by centrifugal force. By reason of the eccentric arrangement of cutter 32 within cutter 12 the blades of cutter 32 are thus brought into shearing engagement under a predetermined pressure with a circumferentially circumscribed portion of cutter 12, which is also the portion thereof provided with slots. During the remainder of the rotation thereof the cutter blades are out of engagement with the surface of cutter 12 so as to reduce the amount of energy required to overcome the friction between the cutters. The operation of the razor is otherwise identical to that of the previously described embodiments.

15 Although but a few embodiments of the present invention have been illustrated and described, it will be apparent to those skilled in the art that various changes and modifications may be made therein without departing from the spirit of the 20 invention or from the scope of the appended claims.

It is claimed and desired to secure by Letters Patent:

1. A safety razor comprising a stationary cutter, a rotary cutter, an electric motor having a stator connected with said stationary cutter and having a rotor connected with said rotary cutter, said stator and said rotor being relatively axially displaced to produce on said rotary cutter a 30 thrust urging said rotary cutter into shearing engagement with said stationary cutter.

2. A safety razor comprising a stationary cutter having a wall provided with slots, each said slot having an elongated rectangular portion extending through the thickness of said wall and terminated by a portion flaring outwardly from the slot, the last said portion being of variable depth less than the thickness of said wall, a movable cutter arranged adjacent said stationary 40 cutter and having cutting edges for cooperating with the edges of the rectangular portions of said slots, and means for actuating said movable cutter in shearing engagement with said stationary cutter.

45 3. A safety razor comprising a hollow frustoconical stationary cutter, a rotary cutter arranged within said stationary cutter eccentrically with respect thereto, and means for causing rotation of said rotary cutter, whereby said rotary cutter is brought into shearing engagement with a circumferentially circumscribed portion of said stationary cutter.

50 4. A safety razor comprising a hollow frustoconical stationary cutter, a resilient rotary cutter arranged within said stationary cutter eccentrically with respect thereto, and means for caus-

ing rotation of said rotary cutter whereby said rotary cutter is urged by centrifugal force into shearing engagement with a circumferentially circumscribed portion of said stationary cutter.

5 5. A safety razor comprising a hollow frustoconical stationary cutter, a rotary cutter arranged within said stationary cutter concentrically with respect thereto, and means for causing rotation of said rotary cutter, the inner surface of said stationary cutter being circumferentially so stepped as to be in contact with said rotary cutter over a circumferentially circumscribed area thereof for cooperating with said rotary cutter in shearing hair and for guiding said rotary cutter.

10 15 6. A safety razor comprising a hollow stationary cutter, a rotary cutter arranged within said stationary cutter, means for causing rotation of said rotary cutter, a fan having a suction passage connected with the space within said stationary cutter and having a discharge passage, a bag permeable to air connected to said discharge passage to collect hair sheared by said cutters, and means for preventing the return by gravity of hair from said bag into said fan.

20 25 7. A safety razor comprising a hollow stationary cutter, a rotary cutter arranged within said stationary cutter, means for causing rotation of said rotary cutter, a fan having a suction passage connected with the space within said rotary cutter and having a discharge passage, a bag permeable to air connected to said discharge passage to collect hair sheared by said cutters, and a yieldable flap in said discharge passage for opening said passage only when said fan is operating.

30 35 8. A safety razor comprising a hollow frustoconical stationary cutter, a rotary cutter arranged within said stationary cutter and comprising a disc portion revoluble about the axis thereof and a plurality of resilient cutting blades integral with said disc, and means for causing rotation of said disc whereby said blades are urged by centrifugal force into shearing engagement with said stationary cutter.

40 45 9. A safety razor comprising a hollow frustoconical stationary cutter, a rotary cutter arranged within said stationary cutter eccentrically with respect thereto and comprising a disc portion revoluble about the axis thereof and a plurality of resilient cutting blades integral with said disc, and means for causing rotation of said disc whereby said blades are urged by centrifugal force into shearing engagement with a circumferentially circumscribed area of said stationary cutter.

50 55 JOSEPH L. BRONSTEIN.
